UNITED STATES PATENT OFFICE

2,591,599

STRUCTURE FOR DRILLING WELLS IN
DEEP WATER

Mercer H. Parks, Houston, Tex., assignor, by
mesne assignments, to Standard Oil Development
Company, Elizabeth, N. J., a corporation
of Delaware

Application August 25, 1949, Serial No. 112,237

4 Claims. (Cl. 61—46)

1

The present invention is directed to a barge-type structure which is adapted to have drilling apparatus mounted thereon to be used in drilling wells in deep water. More particularly, the invention is directed to a barge-like structure which is adapted to be used in drilling wells on submerged areas of the continental shelves of North America.

It has been known heretofore to drill wells on submerged lands. For example, Gilliasso in U. S. 1,681,533 has described a barge structure for submarine drilling operations in which the structure is provided with an open bay through which a drilling operation may be conducted. Gilliasso provides side pontoons for controlling the submergence and floating of his apparatus and has taught that his barge may be compartmentalized for controlling the sinking and floating operations. The Gilliasso apparatus is particularly adapted to conduct drilling operations in relatively shallow waters and has not been adapted to drilling operations where the depth may be 10 feet to 100 feet or more.

Crites et al. U. S. 2,237,387 have also taught the provision of a drilling barge. The feature of the Crites et al. apparatus is to provide tubular columns through which anchors may extend to the floor of the body of water on which the drilling operation is to be conducted. Crites et al.'s drilling barge remains buoyant during the operation and is supported by the tubular columns which piling members telescope to give support thereto.

It will be seen that the apparatus of the prior art has many disadvantages which make them largely unsuitable for conducting drilling operations in deep waters such as may be encountered off Coastal Louisiana and Texas.

It is, therefore, the main object of the present invention to provide an improved barge structure on which a drilling operation may be conducted.

It is another object of the invention to provide a drilling barge which may be sunk and floated under controlled conditions.

A still further object of the invention is to provide an improved structure for conducting operations in deep water which gives controlled support to the drilling apparatus.

Another object of the present invention is to provide a structure for conducting drilling operations which serves as a reservoir for fuels and fluids required in the drilling operation.

Other objects will become apparent from a reading of the description taken with the drawing in which

2

Fig. 1 is an isometric view of the apparatus of the present invention with parts cut away;

Fig. 2 is a sectional view of one of the tubular columns forming a part of the apparatus of the present invention; and

Fig. 3 is a detail of a portion of the apparatus of Fig. 2.

In the several figures of the drawings, identical numerals will be employed to designate identical parts.

The principal parts of the apparatus include a barge defining outer water tight compartments arranged along corresponding parallel sides thereof with inner watertight compartments surrounded by said other compartments. Vertically arranged tubular columns extend through the barge structure and define vertical passageways. The tubular columns support a platform defining a bay or opening above which a drilling rig may be located. The bay or opening in the platform corresponds with a similar opening in the barge itself to allow a drilling operation to be conducted therethrough. It is understood that the bay or opening may be a slot. The tubular columns are adapted to provide buoyancy for the structure when it is being floated or sunk and are provided with valved means therein adjacent the lower end thereof which are controlled from the platform. Second valve means are provided adjacent the upper end thereof for introduction of water or air thereto as may be desired. A second platform may be supported beneath the first platform from which the manifold controls may be operated if desired; such a second platform offers the advantage that by using it the first platform may be kept free from unnecessary obstructions.

Referring now to the drawing and especially to Fig. 1, numeral 11 designates a barge structure which is shown resting on the bottom 12 of a body of water 13. Arranged on barge 11 vertically thereon and extending therethrough are tubular columns 14 which are adapted to support a first platform 15 and a second platform 16; platforms 15 and 16 and barge 11 define respectively openings 17, 18, and 19 through which a drilling operation may be conducted and which allow removal of the structure from a completed well by a sidewise movement.

It will be seen that barge 11 defines a plurality of watertight compartments A, B, C, and D. Compartments A may extend along the long side of the rectangular shape barge except for opening 19 and may or may not be compartmentalized further. Compartments B extend along the short sides of the barge, while compartments C may be designated as inner compartments and

are surrounded by compartments A and B. Compartments D are arranged adjacent the opening 19 and may be said to be surrounded or partially surrounded by compartments C. Compartments D are arranged to provide support for a drilling rig which may be located above opening 17 on platform 15.

Barge 11 is provided with two valved manifolds 20 and 21. Manifold 20 is provided with valves 20a and communicates with compartments A, B, C, and D and may allow ingress thereto of air, fresh water, salt water or oil as may be desired. Manifold 21, similar to manifold 20, is provided with valve 21a and communicates with compartments A, B, C and D and allows discharge therefrom of the contents thereof by introduction of air or gas through inlet 22 controlled by valve 22a communicating with intake manifold 23 which in turn communicates with manifold 20. Fresh water may be introduced to any of the several compartments through intake line 24 controlled by valve 24a which in turn also communicates with intake manifold 23, while salt water may be introduced to any of the several compartments by intake line 25 controlled by valve 25a which likewise communicates with line 23. The contents of the several compartments may be discharged by suitable manipulation of valve 22a in line 22 to admit air and by manipulation of the valves 20a controlling manifold 20 and valves 21a of manifold 21, allowing discharge from manifold 21 into line 26 controlled by valve 26a which, under these conditions, would be in the open position.

Referring to Figs. 2 and 3 it will be seen that tubular column 14 is provided with a cover plate 27 and a plug member 28 located adjacent the upper end thereof. Arranged in and adjacent the lower end of tubular member 14 is valve means 30 which is controlled by valve control means 29 through valve rod 30' extending the length of the tubular member. Opening valve 30 allows water to enter the member 14 through a bottom opening 30a thereof and flood same. Tubular member or column 14 is also provided with an inlet line 31 controlled by valve 32 and an outlet line 33 controlled by valve 34 which allows water or air to be introduced thereto and air to be discharged therefrom. Valve 32 and 34 may be controlled either from platform 15 or platform 16.

It is contemplated that compartments A may be subdivided if desirable and are designed to displace slightly less water than the total weight of the structure and any auxiliary material which may be located on the platforms. Compartments A extend along the long side of the barge to give maximum stabilization thereof.

Compartments B lay along the short side of the barge and are designed so that their combined water displacement will be in excess of the total weight displaced by the barge structure and other equipment carried thereby. Compartments C are surrounded by compartments A and B and are arranged to give maximum bracing and strength to the structure, while compartments D are constructed adjacent to columns 14 supporting heavy loads such as a drilling rig arranged above opening 19 thereof.

In operation of the apparatus of the present invention the barge 11 provided with tubular columns 14 and other structural equipment is launched into a suitable body of water and may be towed to a previously arranged location. On or before reaching the location compartments C

and D may be pumped full of fresh water which will eventually be used in conducting the drilling operation. This loading submerges the barge 11 until it is nearly awash. It is then secured directly above the point on the ocean floor or body of water where it is to rest and fresh water is pumped as required into compartments B to level the barge and bring it completely awash. At this point the inner columns 14 may be connected through suitable valves and lines from upper ends to a common control point and the valves corresponding to valve 30 are opened and allow water to enter as air is let off at the top. Inasmuch as the outer columns 14 arranged along the long and short sides of the barge are closed at the bottom, these outer columns may provide buoyance and stability against overturning to the structure as submergence increases. Thus the barge structure may be sunk under control through the admission of relatively small quantities of water through the lower ends of the columns 14 by valving air off the top thereof. The valve manifold for this operation would suitably be connected to an air compressor or the like so that the water could be forced from any of these columns as it is required to level the structure or raise it. If it becomes desirable to load the inner columns with fresh water that may be accomplished by pumping in through the top valves and if this becomes necessary other means, such as air lifts, for removing the water from the columns may be provided.

It is contemplated as a desirable feature of the operation of the present invention that compartments A and B may be pressurized with a fluid lighter than water, possibly a gaseous fluid such as air, during submergence to counterbalance external hydrostatic pressure and prevent collapse. Such pressures may be maintained by automatic controls.

During drilling operations it is desirable that the fluid in compartments A maintained under pressure be fuel oil inasmuch as these compartments would not contain water when they are pressurized with air or other gas. When fuel oil is stored in compartments A it may be lifted to the point of use by pressure maintained over the fluid such as pressures imposed thereon by inert gas such as nitrogen. Although not shown in the drawing, it may be desirable to provide a separate manifold for the fuel oil to prevent contamination with water.

Compartments B, C and D under all operations may serve as a supply for fresh water which may be lifted by air pressure automatically maintained and introduced through intake manifold 23 by line 22.

It is contemplated that compartments D may serve to give additional support to a drilling rig supported by columns 14 adjacent to opening 19. Thus when the columns 14 are loaded with a drilling rig and excessive loads provided, this excessive loading may be compensated for by providing buoyancy by pumping out some of the water contained therein and replacing it by a lighter fluid such as air.

It will be apparent from the design of my improved structure that tubular columns 14 may be used as conduits or jets for drilling operations if the inner valve means are removed. It is contemplated that the valves may be removable as a unit. It is also contemplated that tubular columns 14 may be used to free the barge from the floor of the sea by jetting fluid under the barge

when it is desired to raise the structure and float it to a new location.

While the preferred embodiment of my invention shows a barge of rectangular shape, it is within the purview of my invention to provide a structure embodying a barge which is substantially square. In short, the barge may be constructed with each side of the same length with parallel sides thereto. In the embodiment where the barge structure is square with each side of same length, it will be desirable to provide watertight compartments arranged along corresponding sides thereof with inner compartments surrounded by the outer compartments. It may be desirable to provide compartments along two of the parallel sides running the length of the structure whereas on the other parallel sides the compartments may similarly run the length of the structure, but may be further compartmentalized. The tubular columns where the barge is square may be arranged similarly to the preferred embodiment shown in the several figures of the drawing.

The nature and objects of the present invention having been completely described and illustrated, what I wish to claim as new and useful and to secure by Letters Patent is:

1. A structure adapted for drilling wells in deep water which comprises a barge defining first outer watertight compartments arranged along first parallel sides thereof, second outer watertight compartments arranged along second parallel sides thereof and inner watertight compartments surrounded by said outer compartments, tubular columns vertically arranged on said barge defining vertical passageways extending therethrough, a platform supported by said tubular columns, a first and second pipe manifold arranged on said barge fluidly communicating with said compartments, means for controlling said manifolds from said platform, a plug disposed in said tubular columns adjacent said platform, first valved means disposed in said tubular column adjacent a lower end thereof and adapted to be controlled from said platform, and second valved means arranged in an inlet and an outlet line for said tubular columns fluidly communicating therewith adjacent an upper end of said tubular columns, said platform and said barge defining openings arranged one above another through which a drilling operation may be conducted.

2. A structure in accordance with claim 1 in which the inner compartments define watertight compartments arranged adjacent the opening in said barge adapted to support the weight of a drilling rig.

3. A structure adapted for drilling wells in deep water which comprises, a rectangular shaped barge defining first outer watertight compartments arranged along the long sides thereof, sec-

ond watertight compartments arranged along the short sides thereof and inner watertight compartments surrounded by said outer compartments, tubular columns vertically arranged on said barge defining vertical passageways extending therethrough, a first and a second platform supported by said tubular columns, a first and second pipe manifold arranged on said barge fluidly communicating with said compartments, means for controlling said manifolds from said second platform, a plug disposed in said tubular columns adjacent said first platform, first valved means disposed in said tubular column arranged adjacent a lower end thereof and adapted to be controlled from said first platform, and second valved means arranged in an inlet and an outlet line for said tubular columns fluidly communicating therewith adjacent an upper end of said tubular columns and adapted to be controlled from said second platform, said first and second platforms and said barge defining openings arranged one above another through which a drilling operation may be conducted.

4. A structure adapted for drilling wells in deep water which comprises a barge defining first outer watertight compartments arranged along first parallel sides thereof, second outer watertight compartments arranged along second parallel sides thereof and inner watertight compartments surrounded by said outer compartments, tubular columns vertically arranged on said barge defining vertical passageways extending therethrough, a first and second platform supported by said tubular columns, a first and second pipe manifold arranged on said barge fluidly communicating with said compartments, means for controlling said manifolds from said second platform, a plug disposed in said tubular columns arranged adjacent said first platform, first valve means disposed in said tubular column arranged adjacent a lower end thereof and adapted to be controlled from said first platform, and second valve means arranged in an inlet and an outlet line for said tubular columns fluidly communicating therewith adjacent an upper end of said tubular columns and adapted to be controlled from said second platform, said first and second platforms and said barge defining openings arranged one above another through which a drilling operation may be conducted.
